UNITED STATES PATENT OFFICE.

LEONARD TRACY CRABTREE, OF CRANDON, WISCONSIN.

HEATER.

1,137,584.

Specification of Letters Patent. Patented Apr. 27, 1915.

Application filed August 23, 1913. Serial No. 786,264.

To all whom it may concern:

Be it known that I, LEONARD TRACY CRABTREE, a citizen of the United States, and a resident of Crandon, in the county of 5 Forest and State of Wisconsin, have invented a new and Improved Heater, of which the following is a full, clear, and exact description.

The present invention is designed to provide a heater having the maximum heating 10 capacity in proportion to the fuel consumption.

A further design of the invention is to provide a heater that can be utilized for 15 effectively ventilating a room or rooms.

The invention further has for its design to provide a heater having an improved heat-insulating casing.

The invention will be particularly explained in the specific description following.

Reference is to be had to the accompanying drawings forming a part of this specification, in which similar characters of reference indicate corresponding parts in 25 all the views, and in which—

Figure 1 is a vertical section of a heater embodying my invention; Fig. 2 is a front elevation partly in section; Fig. 3 is a sectional plan view.

In constructing a heater in accordance 30 with my invention, an outer casing is provided, comprising an exterior shell 10 and an inner shell 11, both being formed preferably of sheet metal, a layer 12 of asbestos around the inner shell, and a layer 12^a of pulp around the layer of asbestos, the two metallic shells inclosing the said layers. The construction of the casing is designed 35 to afford the maximum heat-insulating qualities. The casing is supported on suitable legs 13, and it is L-shaped, consisting of a horizontal body 14 and a vertical member 15.

Within the horizontal portion 14, a tubular fire-box 16 is disposed, concentric with 40 and spaced from the outer casing. An up-take 17 extends from the rear end of the fire-box and communicates at its upper end with a tubular outlet 17^a which may lead to 45 a chimney.

Surrounding the fire-box—between the same and the outer casing—is a spiral air

flue 18, and, similarly, a spiral flue 19 surrounds the up-take 17 and communicates with the flue 18. Leading to the spiral flue 55 18 is an inlet pipe 20 extending to the exterior of the heater, the inlet, in practice, extending to the exterior of the building or to a fresh air space below the floor, thereby to afford an ample supply of fresh air to 60 the flues 18—19, to be heated. There is a lateral branch inlet 21 to the main fresh air inlet 20, at a point immediately adjacent to the heater, and preferably beneath the same, so as to be located adjacent to the floor 65 A of the room.

Dampers 22 and 23, of any approved form are provided in the main inlet 20 and branch inlet 21, either of which dampers may be opened or closed. If the damper 23 70 be closed and the damper 22 opened, fresh air may freely enter through the spiral air flues, through the main air inlet 20. On the other hand, if the damper 22 be closed and the damper 23 be opened, air will be taken 75 in through the branch inlet 23, to be again heated and discharged at the top of the heater. The provision of the branch inlet is for the purpose of heating the air in a room with a minimum expenditure of fuel. 80 In fact when the fire-box and air flues have been thoroughly heated, the insulated casing conserves the heat so that without any further expenditure of fuel, the air may be continuously taken in through the branch 85 inlet and again discharged, thus fully utilizing the hot elements of the heater without admitting fresh air from the outside to cool the same.

At the top of the spiral flue 19 of the up-take, an air chamber is produced by vertically spaced horizontal plates or partitions 24 having openings 25 for the outlet of the air. The provision of the hot air chamber above the spiral flue 19 will result in the air 90 therein being highly heated and tend to induce the flow of air through the air flues. Above the upper partition 24 a flaring deflector 26 is provided around the tubular outlet 17^a of the up-take, the said deflector 95 being spaced from the top of the heater casing and serving to deflect the out-flowing air in every direction.

The front 27 of the heater is formed simi-

larly to the described outer casing of the fire-box and up-take, having the inner and outer shells 10^a, 11^a, the layer 12^b corresponding with the layer 12, and the layer 12^c of pulp corresponding with the layer 12^a. The front is provided with an opening 28 leading to the fire-box, and with a fire door 29 hinged at 29^a. Also, there is provided an inlet 30 and ash-door 31 in the front, below the fire-box.

10 A grate is constructed at the front end of the tubular fire-box 16, said grate comprising longitudinal bars 32 set in the bottom wall of the fire-box, and arranged in 15 transversely curved order, so as to constitute a concaved grate bottom. At the inner end of the bars 32 a transverse member 33 rises from the bottom of the fire-box and constitutes an inner end grate, there being suitable 20 openings in said transverse member.

In order that the heater may constitute a 25 ventilator, I provide an air inlet 34 which extends inwardly through the outer casing, through the intermediate air flue 18 and through the wall of the fire-box 16 to the interior of the latter. The inlet is provided with a suitable damper 35 and the outer end is close to the bottom of the heater and hence will be close to the floor of a room, so that 30 when the damper 35 is open, the contaminated air near the floor will pass into the fire-box and be discharged through the outlet 17^a, thereby effectively ventilating the room since fresh air may be admitted continuously through the inlet 20 and flues 35 18—19.

Below the grate a suitable ash box 36 is constructed, to receive an ash pan, to be 40 inserted through the opening 30. It will thus be seen that a very effective heater is provided which may be readily converted into a ventilator. It is to be understood that when there is no fire in the grate and it is desired to ventilate, a gas jet or lamp 45 may furnish the necessary heat for inducing the ventilating current through the ventilating inlet 34.

That the results obtained by my improved 50 heater, and its advantages may be the better understood, I would explain that the described construction is highly efficient in maintaining a room at a given temperature after the room has been initially heated by the heater. Assuming that the room has 55 been heated to, say, 70° F., and the spiral flue and fire box to be at a higher heat than the air in the room, from an initial consumption of fuel, then by shutting the draft openings and charging the heater with fuel, 60 the consumption of the fuel will be very slow, as will be obvious, and at the same time the heat of the fuel and adjacent metal parts will, owing to the insulated covering, part with their heat only to the heated air 65 of the room being circulated through the

flues. Inasmuch as the air of the room is itself already heated, it will in passing through the flues deprive the latter of but little heat to maintain the temperature of the air in the room, and thus the heater will 70 serve to maintain the room in a heated condition with the least possible consumption of fuel.

I do not wish to be understood as claiming a horizontal spiral flue *per se*, nor as 75 claiming a spiral up-take flue *per se*. Neither the one nor the other will suffice to maintain a room heated in the manner I describe, for the reason that it is impractical to provide a horizontal flue of sufficient 80 length to be efficient with the drafts of the stove closed, and it is impossible also, in any ordinary room, to construct a separate up-take alone of a length to be efficient. In fact, the spiral up-take if employed 85 alone, will, in practice, lose the greater part of its heat to the air at the bottom of the flue, and the upper end of the flue will remain comparatively cool. I have found that a horizontal flue combined with 90 a communicating up-take flue, both spiral, can be given in a comparatively small stove, a total effective length of thirty feet or more, and by combining the two, I can maintain a comfortable temperature in a 95 room, even in cold weather, by a heater of comparatively small dimensions.

The combined use of the inner layer of asbestos or equivalent non-combustible, heat-insulating material, and the layer formed of 100 wood pulp, these being arranged between the inner metallic wall and the outer metallic shell, will so conserve the heat of the spiral flues as to very materially contribute to the effectiveness of the horizontal and 105 vertical flues.

Having thus described my invention, I claim as new, and desire to secure by Letters Patent:—

1. A heater, comprising an approximately 110 horizontal tubular fire box, a tubular up-take forming an upward continuation of the horizontal fire box, a spiral air flue surrounding the fire box, and a communicating spiral air flue surrounding the tubular up-take, the spiral flue of the horizontal fire box having an inlet adjacent to the front of the heater, to permit air to enter said flue from the room in which the stove is located, and there being an outlet for the 120 air at the upper end of the spiral air tube of the up-take.

2. A heater having an approximately 125 horizontal fire box and a communicating up-take, the fire box and up-take having communicating air-heating flues surrounding said fire-box and up-take, there being an inlet to the air flue of the fire box near the front of the heater, and an outlet for the air at the upper end of the flue of the 130

up-take, the said air flues having a casing comprising a metallic inner wall, a layer of non-combustible, heat-insulating material directly applied to the outer side of said wall, a layer formed of wood pulp applied to said layer of non-combustible material, and a sheet metal inclosing shell around said layer of wood pulp.

In testimony whereof I have signed my name to this specification in the presence of 10 two subscribing witnesses.

LEONARD TRACY CRABTREE.
